UNITED STATES PATENT OFFICE.

ADOLPH SCHERTZ, OF YOUNGSTOWN, OHIO.

AEROPLANE.

Application filed September 6, 1928. Serial No. 304,297.

The present invention relates to an aero-plane and has for its prime object to provide an aeroplane for flight over the ocean and with this end in view I have provided 5 a structure capable of landing on the water and maneuvering on the water and further have provided a structure whereby great sustaining power or capacity is required in the air, because of air pockets in the fuselage 10 and wings and specially designed air outlets or escapes.

Another very important object of the invention resides in the provision of an elevator and a rudder formed with air spaces and 15 air outlets at the exit thereof, so as to attain the maximum efficiency and maneuvering in the air.

Another very important object of the invention resides in the provision of control 20 means of the nature just mentioned which are frames hingedly mounted to normally return to and stay in a predetermined position for horizontal flight so as to relieve the aviator of considerable strain during a long 25 flight when the plane is maintaining a straight ahead horizontal flight.

Another very important feature of the invention resides in the provision of a landing drag stick, so mounted and constructed 30 that it may function as a rudder in the water.

A still further important object of the invention resides in the provision of an aero-plane of this nature which is simple in its 35 construction, compact and convenient in its arrangement of parts, strong and durable, thoroughly efficient and reliable in use and operation, and otherwise well adapted to the purpose for which it is designed.

With the above and numerous other objects in view, as will appear as the description proceeds, the invention resides in certain novel features of construction, and in the combination and arrangement of parts 45 as will be hereinafter more fully described and claimed.

In the drawings:

Figure 1 is a top plan view of an aero-plane embodying the features of my invention.

Figure 2 is a bottom plan view thereof.

Figure 3 is a side elevation thereof.

Figure 4 is a longitudinal vertical section therethrough showing a portion of the front 55 end of the fuselage in side elevation.

Figure 5 is a fragmentary vertical transverse section.

Figure 6 is a fragmentary vertical longitudinal section through the rear portion of the superstructure, showing the means for 60 mounting the rudder.

Figure 7 is a detail top plan view showing the door of the baggage room in an open position with the rudder removed.

Figure 8 is a longitudinal section through 65 one of the wings.

Figure 9 is a detail horizontal section taken substantially on the line 9—9 of Figure 4.

Referring to the drawings in detail, it 70 will be seen that the numeral 5 denotes a hollow fuselage, constructed of sheet metal or any other suitable material and formed so as to taper forwardly and rearwardly from the central portion thereof. Each side 75 of the front tapered portion of the fuselage 5 is formed with elongated air pockets 6 inclining upwardly and forwardly and having the edges thereof corrugated to form outlets or air escapes. A suitable propeller 8 is 80 mounted at the nose of the fuselage and will be driven by suitable prime movers in the fuselage (not shown). A pontoon 9 is mounted on the bottom of the central portion of the fuselage 5 and is hollow having 85 its side walls converging downwardly toward each other to meet in an apex edge.

A landing gear 10 is mounted on the fuselage, below the pontoon 9. The bottom of the rear tapered portion of the fuselage 5 90 is formed with an elongated longitudinal air pocket 11. The edges of the pocket 11 are corrugated as at 12 to form air outlets or escapes.

A superstructure 14 is mounted above the 95 central and forward portions of the fuselage 5 and includes a package compartment 15, an aviator's compartment 16, and a front compartment 17. A casing of triangular formation 18 is hingedly mounted as at 19 100 to the rear of the superstructure, so that it may be swung to one side as indicated to advantage in Figure 7, for the loading and unloading of baggage. Hinged apertured ears 20 are mounted on the rear edge of the casing 18. Below the top of the fuselage 5 there is mounted a bearing 22, by means of arms 23, and in this bearing is a rotatable shaft 24, having a sprocket in the upper end thereof. A pin 25 is insertable in the socket 110

to extend above the fuselage through the hinged apertured ears 21 and to receive hinged ears 26 on a rudder 27. A spring 28 is associated with the rudder and the pin 25 so as to maintain the rudder 27 normally straight to guide the aeroplane straight ahead. A sprocket 29 is provided on the shaft 24, so that a chain 30 may be trained thereover for controlling the rudder.

10 Obviously the pin 25 may be removed to remove the rudder so that the casing 18 may be swung to one side for loading or unloading the baggage. Platforms 32 extend along the sides of the superstructure 14 and have 15 railings 33 rising from the outer edges thereof. The rudder 27 is concaved inwardly on both sides to form air pockets 34 and the edges are corrugated as at 35, to provide air outlets or escapes. This rudder is provided 20 with straight upper and rear edges at right angles to each other and a top edge which is curved downwardly from the rear edge to the hinged end.

An elevator 37 is spring hingedly mounted 25 as at 38 on the rear end of the fuselage 5 and the rear edges of fins 39 projecting laterally from the rear end of the fuselage. The elevator 37 is provided with a concaved lower surface forming an air pocket 40 and a corrugated edge 41 forming the air escape or outlet. The fins are concaved on their bottom surfaces as indicated at 41 and the edges are corrugated as at 42 to provide air escapes or outlets. The rudder 40 is operated 30 by means of a pin or shaft 45, and a sprocket and chain mechanism 46.

A combined landing drag stick and rudder 47 has its upper end journaled in a bearing 48, at the rear of the fuselage to depend 40 downwardly therefrom and incline slightly rearwardly and the bottom end curves rearwardly as at 49. A brake structure 50 inclining downwardly and rearwardly from the rear portion of the fuselage has a collar 45 51 in which the lower portion of the member 47 is rockable. A chain and sprocket mechanism 52 is provided, for rotating this member 47 when in the water, so as to function as a rudder, for guiding the floating air 50 ship on the water.

Bird like wings 57 project one from each side of the central portion of the fuselage. Each wing has a straight rear edge at right angles to the median longitudinal dimension 55 of the aeroplane and a curved front edge converging gradually toward the outer end of the straight edge terminates in a point therewith. These wings are of hollow construction, including upper seats 58 and lower 60 seats 59. These seats are somewhat concentrically curved but meet at their rear and forward edges so as to be air tight. The forward edge of each wing is formed by having the seats 58 and 59 abruptly converge toward 65 each other and terminate in abutments as is

indicated at 60 so as to provide an air non-resisting edge. These lower seats 49 are provided with air pockets, and the rear and inner edges thereof are corrugated as at 61 to provide air escapes or outlets. Because of 70 the wing construction just described in combination with the air pockets of the fuselage, it will be seen that this aeroplane is possessed of considerable soaring capacity without the aid of the propeller, so that if the aeroplane 75 is travelling at a sufficient height and motor trouble occurs, it is probable that repairs could be made before an emergency landing.

Rising from the superstructure 14 are two poles 63, which may be used to mount an antenna 64 for a radio receiving and sending set, and in an emergency these poles may be used as a sail when the plane has made an emergency landing in the water, so that with the aid of such a sail and the rudder afforded by the member 47, progress could be made.

It is thought that the construction, utility and advantages of this invention will now be quite apparent to those skilled in this art, without a more detailed description thereof.

The present embodiment of the invention has been disclosed in detail, merely for the purposes of exemplification, since in actual practice it will attain the features of advantage enumerated as desirable in the statement of the invention and the above description.

It will be apparent that changes in the details of construction and in the combination and arrangement of parts may be resorted to, without departing from the spirit or scope of the invention as hereinafter claimed or sacrificing any of its advantages.

Having thus described my invention, what I claim as new is;

1. In an aeroplane of the class described, a fuselage having air pockets therein with air escapes formed by corrugated edges.

2. In an aeroplane of the class described, a fuselage having air pockets therein with air escapes formed by corrugated edges, and wings projecting from the fuselage having air pockets in the bottom thereof with corrugated rear and inner edges to form air escapes.

3. In an aeroplane of the class described, a fuselage having air pockets therein with air escapes formed by corrugated edges, and wings projecting from the fuselage having air pockets in the bottom thereof with corrugated rear and inner edges to form air escapes, an elevator member, and a rudder member hingedly mounted on the fuselage, said members being provided with air pockets having corrugated edges forming air escapes.

4. In an aeroplane of the class described, a fuselage having air pockets therein with air escapes formed by corrugated edges, and wings projecting from the fuselage having

air pockets in the bottom thereof with corrugated rear and inner edges to form air escapes, elevator members, and a rudder member hingedly mounted on the fuselage, said members being provided with air pockets having corrugated edges forming air escapes, a hollow pontoon on the bottom of the fuselage, landing gear on the fuselage below the pontoon.

10 5. In an aeroplane of the class described, a fuselage having air pockets therein with air escapes formed by corrugated edges, and wings projecting from the fuselage having air pockets in the bottom thereof with corrugated rear and inner edges to form air escapes, an elevator member, and a rudder member hingedly mounted on the fuselage, said members being provided with air pockets having corrugated edges forming air escapes, a hollow pontoon on the bottom of the fuselage, landing gear on the fuselage below the pontoon, a combined landing drag stick and rudder member rockably mounted on the rear of the fuselage and having a curved rearward lower end, and means for rocking said combined member.

15

20

25

6. In an aeroplane of the class described, a fuselage having air pockets therein with air escapes formed by corrugated edges, and
30 wings projecting from the fuselage having air pockets in the bottom thereof with corrugated rear and inner edges to form air escapes, an elevator member, and a rudder member hingedly mounted on the fuselage,
35 said members being formed with air pockets having corrugated edges forming air escapes, a hollow pontoon on the bottom of the fuselage, landing gear on the fuselage below the pontoon, a combined landing drag
40 stick and rudder member rockably mounted on the rear of the fuselage and having a curved rearward lower end, and means for rocking said combined member, a brake structure extending from the fuselage, a collar on the end of the brake structure circumjacent the base portion of the combined member.

7. In an aeroplane of the class described, a fuselage having air pockets therein with air escapes formed by corrugated edges, and wings projecting from the fuselage having air pockets in the bottom thereof, with corrugated rear and inner edges to form air escapes, an elevator member, and a rudder member hingedly mounted on the fuselage, said members being provided with air pockets having corrugated edges forming air escapes, a hollow pontoon on the bottom of the fuselage, landing gear on the fuselage below the pontoon, a combined landing drag stick and rudder member rockably mounted on the rear of the fuselage and having a curved rearward lower end, and means for rocking said combined member, a brake structure extending from the fuselage, a collar on the

end of the brake structure circumjacent the lower portion of the combined member, a superstructure mounted on top of the fuselage and including a plurality of compartments.

8. In an aeroplane of the class described, a fuselage having air pockets therein with air escapes formed by corrugated edges, and wings projecting from the fuselage having air pockets in the bottom thereof with corrugated rear and inner edges to form air escapes, an elevator member, and a rudder member hingedly mounted on the fuselage, said members being provided with air pockets having corrugated edges forming air escapes, a hollow pontoon on the bottom of the fuselage, landing gear on the fuselage below the pontoon, a combined landing drag stick and rudder member rockably mounted on the rear of the fuselage and having a curved rearward lower end, and means for rocking said combined member, a brake structure extending from the fuselage, a collar on the end of the brake structure circumjacent the base portion of the combined member, a superstructure mounted on the top of the fuselage and including a plurality of compartments, a casing hingedly mounted on the rear of the superstructure, and means for hingedly mounting the rudder member on the rear end of the casing in a detachable manner.

9. In an aeroplane of the class described, a fuselage having air pockets therein with air escapes formed by corrugated edges, and wings projecting from the fuselage having air pockets in the bottom thereof with corrugated rear and inner edges to form air escapes, an elevator member, and a rudder member hingedly mounted on the fuselage, 100 said members being provided with air pockets having corrugated edges forming air escapes, a hollow pontoon on the bottom of the fuselage, landing gear on the fuselage below the pontoon, a combined landing drag 105 stick and rudder member rockably mounted on the rear of the fuselage and having a curved rearward lower end, and means for rocking said combined member, a brake structure extending from the fuselage, a collar on the end of the brake structure circumjacent the base portion of the combined member, a superstructure mounted on the top of the fuselage and including a plurality of compartments, a casing hingedly 110 mounted on the rear of the superstructure, and means for hingedly mounting the rudder member on the rear end of the casing in a detachable manner, spring means associated 115 with the rudder and elevator members to maintain them in a position to cause the aeroplane to fly in a straight ahead horizontal position. 120 125

In testimony whereof I affix my signature,

ADOLPH SCHERTZ 130
